AUTOMATIC STARTER CONTROL FOR
INTERNAL-COMBUSTION ENGINESWalter A. Wolf, Logansport, Ind., assignor to
Switches, Inc., Logansport, Ind., a corporation
of Indiana

Application September 30, 1953, Serial No. 383,275

5 Claims. (Cl. 290—36)

1

My invention relates to improvements in starter switches for internal combustion engines. More particularly, my invention relates to improvements in the type of starter switches wherein an electromagnet energized by an engine-driven generator is relied upon to hold the starter switch in the open circuit position when the engine is running.

In the prior art devices of this general class, it is essential that a minimum supply of energy sufficient to operate the electromagnet be forthcoming from the generator both at idling and throughout the entire range of operating engine speeds; otherwise, the switch will close to engage the starter mechanism. This frequently results in stripping the teeth from the flywheel of the engine or in other serious damage to the starting mechanism. While in theory the generator may be set to deliver ample energy at all engine speeds to disable the starter, and while this performance is usually obtained in the case of new equipment, such factors as loose generator belts, improper setting of the generator, and worn brushes, may cause the generator voltage output to drop at idling and part throttle engine speeds to a level at which the electromagnet will not hold the starter switch in the open position.

Accordingly, it is the principal object of my invention to provide a starter switch for internal combustion engines in which the switch is held inoperative at idling and part throttle engine speeds, regardless of the energy supplied by the generator to the electromagnetic device of the switch.

Another object of my invention is to provide a starter switch of the character described which is easy to install, dependable in use, and inexpensive to manufacture.

To the end of achieving these objects, my invention, as installed, comprises (1) a switch for opening and closing the circuit of the starter motor for the engine, (2) energy storing means such as a spring urging the switch into the closed circuit position, (3) movable stop means normally resisting movement of the switch into the closed circuit position, (4) means actuated by the engine throttle control, when the latter sets the engine to operate at high speeds, for moving the movable stop means to allow movement of the switch into the closed circuit position, and (5) electromagnetic means energized by the engine generator to prevent movement of said switch into the closed circuit position, regardless of the position of said movable stop means, as long as the engine is operating at medium and high speeds. In one application of my invention the

2

switch is placed directly in the circuit of the starter motor for the engine. In another application the switch serves as a relay for opening and closing a conventional solenoid starter switch in the starter motor circuit.

5 Furthermore, this invention is an improvement over the invention disclosed in my co-pending application Serial No. 159,526, now Patent No. 2,663,804, granted December 22, 1953, and it provides a construction facilitating mounting of the device by providing all binding posts in substantially the same plane, a screw for connecting the starter switch or relay to its mounting bracket while simultaneously holding a soft ferrous plug within the electromagnet and an improved starter actuating linkage permitting adaptation of my automatic starter for any car whether equipped with a solenoid or other normal type of starter.

Another object of this invention is to provide 10 an automatic starter for inexpensively converting to accelerator starting any car equipped with a push button or key starter and not having accelerator starting, while permitting the original starting equipment to remain undisturbed.

15 In order that my invention may be more fully disclosed, reference is had to the accompanying drawing which illustrates one form of apparatus embodying the foregoing and such other principles, advantages and capabilities as may be pointed out as this description proceeds, or as 20 are inherent in the present invention. For purposes of clarity in exposition, the following description is explicit and the accompanying drawing detailed, but it is distinctly to be understood 25 that said exposition is illustrative only, and that my invention is not restricted to the particular details recited in the specification or shown in the drawing.

In the drawing:

Figure 1 is an elevational view of an automatic 30 starter embodying the invention, an exemplary wiring diagram for use therewith being shown schematically;

Figure 2 is a vertical cross sectional view of 35 the embodiment of Figure 1, illustrating the starter switch in open position;

Figure 3 is a vertical cross sectional view as 40 in Figure 2, but illustrating the switch in starting position;

Figure 4 is an enlarged fragmentary view on 45 the plane of line 4—4 of Figure 1, looking in the direction of the arrows and illustrating the binding post to the generator;

Figure 5 is an enlarged detail view taken on 50 the plane of the line 5—5 of Figure 1 and looking in the direction of the arrows; and

Figure 6 illustrates a second application of my invention, in which it serves as a control rather than as a primary starting switch.

Like reference characters designate like parts in the drawing and in the description of my invention which follows hereafter.

Referring now to the drawing, and more particularly to Figures 2 and 3 thereof, my automatic starter is shown as including a casing 10, a partition 11 and an insulating plate 42 therein, and two binding posts 12 and 13 extending on opposite sides from the casing 10. The binding post 12 secures the contact 16 in place and is insulated from the casing 10 by the insulating washers 14 and 15. The lock washer 17 and nuts 18, 18 fasten the binding post 12 in place, and also provide means for connecting said post 12 to a starter motor 19 of an internal combustion engine through the wiring 20. Similarly, the binding post 13 is insulated from the casing 10 by the insulating washers 22 and 27, and positions the contact 21 as shown. Lock washer 23 and nuts 24, 24 fasten the post 13 in place, and provide means for connecting the binding post 13 to a battery 25 or other source of energy through the wiring 26.

Extending downwardly from the partition 11 and plate 42 is a sleeve 28, in which an armature 29 is slidable. The sleeve 28 supports a carrier or winding spool 30 for the winding 31 of an electromagnet, designated generally by the numeral 32. One end 30 of the electromagnet winding 31 is connected through the binding post 34 and the wiring 35 to the grounded generator 33, which is driven by the internal combustion engine. The insulating washers 59, 59 insulate the post 34 from the casing 10, while lock washer 62a and the nuts 62, 62 both secure the post 34 in place and facilitate connecting it to the generator 33. The other side of the electromagnet winding 31 is connected to the partition 11 by the wiring 36, and is therefore grounded to the casing 10. The electromagnet 32 is so arranged that when the winding 31 is energized by the generator 33, the armature 29 is urged downwardly into the position shown in Figure 2. A spring 37 fits within the bore 38 of the armature 29, to urge said armature 29 upwardly to the position shown in Figure 3. A contact plate 39 is secured to the upper end of the armature 29, by the fastener 40 and the washer 41, but is insulated from said armature 29 by the insulating washers 60, 61.

The binding posts 12, 13 and 34 are all substantially in the same plane and thereby facilitate mounting the automatic starter.

A bonnet 43 is secured to the upper end of the casing 10, and has a flanged opening 44 therein. Also positioned in the upper portion of the casing 10 is an insulating plate 45 and a backing plate 46, which are spaced from the bonnet 43 by the spring 47. A plunger 48 extends through the flanged opening 44 and the bonnet 43, and through the opening 49 in the plates 45 and 46. A spring 50 surrounds the plunger 48, and bears against the shoulder portion 51 thereof to urge the plunger 48 downwardly in the position shown in Figure 2. The spring 50 is purposely made stronger than the spring 37, so that when no external forces are exerted on the plunger 48, said plunger holds the armature 29 in the position of Figure 2, against the opposition of the spring 37.

The casing 10 is secured to a bracket 52 by means of the post portion 81 of a large-headed

5 screw generally designated as 72, and associated lock washer and nut 73, 74. The head or plug 75 of screw 72 extends within the electromagnet 32 and the lower end of spring 37 rests on said head 75. Said head 75 also serves as a stop for armature 29. The head 75 of screw 72 is ferrous and thereby enhances the magnetic effect of the electromagnet 32.

10 The end of the plunger 48 is in turn connected to the accelerator rod 53 of the engine, through clamp 54 which is slidable along the tension coil spring 55 which extends through an eyelet 56 in the clamp 54. The coil spring 55 is of uniform diameter and uniformly closely wound in turns approximately corresponding to the pitch of screw 57, so that screw 57 may be threaded into and retained in the upper end 58 of the spring 55 regardless of the length to which spring 55 is adjusted; and said coil spring 55 is secured to the plunger 48. The length of the spring 55 is preferably such that it is necessary to move rod 53 to substantially the full throttle position before the clamp 54 engages the screw 57 to apply tension on spring 55 to move the plunger 48 to the position illustrated in Figure 3. In other positions of the throttle there will be no effect on plunger 48. Adjustment of the spring 55 to the desired length, depending upon the automobile in connection with which a specific device is to be used, may be achieved merely by removing from the upper end 58 of the spring 55 any undesired length thereof. A spring is utilized for member 55 because it is inexpensive, easy to attach, and slips easily through eyelet 56 even when the motion is angular or not in one plane in relation to bracket 54. The extensibility of spring 55 provides a margin of safety when the installation is carelessly or improperly made.

20 The spring 59, urging the shoulder portion 51 of the plunger 48, forces the armature 29 to the position of Figure 2 by over-powering spring 37. With armature 29 thus depressed, the contact plate 39 is spaced from the contacts 16 and 21 so that no energy can flow from the battery 25 to the starting motor 19.

30 When the accelerator rod 53 is actuated, as for example by fully depressing the accelerator foot pedal, the clamp 54 engages the head of screw 57 and thereby causes the spring 55 to be put under tension, and the plunger 48 is pulled away from the position of Figure 2 to the position of Figure 3. When this occurs, the spring 37 moves the armature 29 upwardly until contact plate 39 bridges the contacts 16 and 21. This completes the circuit between battery 25 and starting motor 19.

40 As soon as the engine starts, the normal reaction of the operator is to allow the accelerator foot pedal which controls the accelerator rod 53 to return to the idling or part throttle position. The plunger 48 thereupon returns to the position of Figure 2, and moves the contact plate 39 away from the contacts 16 and 21, to open the circuit of the starter motor 19. At the same time, the engine drives the generator 33, which energizes the winding 31 of the electromagnet 32. The strength of the magnetic field of the electromagnet 32, augmented by the effect from plug 75, normally is sufficient to move the armature 29 downwardly against the resistance of the spring 37. However, the starter switch does not rely upon the electromagnet 32 to break the contact between the contacts 16 and 21 and the plate 39, since as the engine is started up, the

plunger 48 makes positive this action. Thus, even though the output of the generator 33 at idling or part throttle speed may be insufficient to cause the electromagnet 32 to overcome the upward force of the spring 37, the plunger 48 insures that the circuit of the starter motor 19 remains open, so that said motor 19 cannot engage the starting mechanism of the internal combustion engine because there will be no pulling tension on spring 55.

It is now apparent therefore that during all speeds to which the engine is accelerated, except the highest speed when the accelerator pedal is almost fully depressed, a dual force is active to overcome the resistance of spring 37, thereby maintaining the switch in the position illustrated in Figure 2. In the event that the highest speeds of the engine are reached, a condition not normally prevailing, so that the clamp 54 extends spring 55 to raise the plunger 48 to the position of Figure 2, the output of generator 33 creates a sufficient magnetic field about the armature 29 to overcome the resistance of spring 37, and thereby maintains the contact plate 39 in the position illustrated in Figure 2, unaided by the plunger 48.

While in the application of my invention illustrated in Figures 2 and 3, the contacts 16 and 21 and the contact plate 39 are placed directly in the circuit of the starting motor 19, in most applications it is desirable to use my invention in the manner of a relay, rather than as the primary starter switch. When this is the case, the arrangement shown in Figure 6 may be used to advantage. More particularly, in this application the binding post 12 is connected through the lead 65 to the solenoid post 63 of a conventional solenoid starter switch 64. One terminal 66 of the starter switch 64 is connected to the starter motor 19 through the lead 67, while the other terminal 68 of the switch 64 is connected to the battery 25 or other source of electrical energy through the lead 69. Also connected to the battery 25 through the lead 70 is the other binding post 13 of my device. Since the current flowing to the binding post 13 through the lead 70 is substantially less than the starter motor current, it is practical to interpose the ignition switch 71 in the lead 70.

Using the circuit arrangement of Figure 6, when the plunger 48 is extracted from the casing 10, to close the contact plate 39 against the contacts 16 and 21, current flows from the battery 25 to the solenoid post 63, whereupon the solenoid starter switch 64 closes the circuit between the starter motor 19 and the battery 25. As the internal combustion engine starts up, the operation of a plunger 48 and the related apparatus within the casing 10 is the same as that outlined above in connection with Figures 2 and 3. The only difference between the arrangement of Figures 2 and 3 and that of Figure 6 is therefore one of application rather than principle of operation, in the first instance my invention being used as a primary starter switch, whereas in the second instance it serves as a relay which actuates the primary starter switch.

Having thus fully disclosed my novel automatic starter for internal combustion engines, and illustrated its utility by reference to certain specific applications thereof, I claim as my invention:

1. A starter for the starter motor of an internal combustion engine including a throttle control, a generator driven by said engine, and

70
75

a source of electrical energy for said starter motor, said starter comprising: A casing, a plug and an electromagnet mounted in said casing and energized by said generator as the latter is driven by said engine, a first switch contact connected to said starter motor, a second switch contact connected to said source of electrical energy, an armature in said electromagnet and including a contact member for bridging said first and second switch contacts, said armature being operated by said plug and said electromagnet to open said switch contacts upon energizing said electromagnet, a first spring urging said armature to close said switch contacts, a plunger slid-
10 able in said casing and positioned for engagement of said armature, an end of said plunger extending through said casing, a second spring, said second spring being stronger than said first spring and engaging said plunger to move said plunger into engagement with said armature to open said switch contacts, a bracket for mounting said casing on said engine, a post connecting said bracket to said casing and securing said plug within said electromagnet, and a coil spring
15 interconnecting the outer end of said plunger and said throttle control, tensioning of said coil spring moving said plunger against the resistance of said second spring to permit movement of said contact member to bridge said switch contacts, the strength and initial adjustment of said coil spring being such that the resistance of said second spring is not overcome until said throttle control is in the substantially fully open position, whereby at idling and low engine speeds
20 said second spring is operative to maintain said switch contacts open independent of the influence of said electromagnet on said armature.

2. A starter for the starter motor of an internal combustion engine including a throttle control, a generator driven by said engine, and a source of electrical energy for said starter motor, said starter comprising: A casing, an electromagnet and a plug mounted in said casing and energized by said generator as the latter is driven by said engine, a first switch contact connected to said starter motor, a second switch contact connected to said source of electrical energy, an armature in said electromagnet and including a contact member for bridging said first and second switch contacts, said armature being operated by said plug and said electromagnet to open said switch contacts upon energizing said electromagnet and said plug, a first spring urging said armature to close said switch contacts, a plunger slid-
40 able in said casing and positioned for engagement of said armature, a second spring, said second spring stronger than said first spring and engaging said plunger to move said armature to open said switch contacts, a coil spring connected to said plunger, a screw threaded in the end of said coil spring, and a bracket slidable on said coil spring and secured to said throttle control, the head of said screw being engaged by said bracket to operate said coil spring to pull said plunger only when said throttle control is in substantially fully open position.

3. A starter for the starter motor of an internal combustion engine or the like, substantially as described in claim 1, and further characterized by a screw threaded in the end of said coil spring, said coil spring being of uniform diameter, and a bracket secured to said throttle control and engaging said screw to pull said spring and plunger only at substantially fully open position of said throttle control.

4. A starter control for the starter motor of an internal combustion engine substantially as defined in claim 1 and further characterized by a bracket securable to said throttle control and slidable on said coil spring, the coils of said coil spring being of uniform diameter, an outer end portion of said coil spring being removable, a headed screw threadable in the remaining portion of the outer end of said coil spring, the pitch of said screw being approximately the same as the pitch of the coils of said coil spring, the head of said screw being engageable by said bracket to pull said coil spring only at substantially fully open position of said throttle control, the adjacent coils of said coil spring touching each other at substantially all other positions of said throttle control.

5. A starter for the starter motor of an internal combustion engine including a throttle control, a generator driven by said engine, and a source of electrical energy for said starter motor, said starter comprising: A casing, an electromagnet mounted in said casing and energized by said generator as the latter is driven by said engine, a first switch contact connected to said starter motor, a second switch contact connected to said source of electrical energy, an armature in said electromagnet and including a contact member for bridging said first and second switch contacts, said armature being operated by said electromagnet to open said switch contacts upon energizing said electromagnet, a first spring urging said armature to close said switch contacts, a plunger slidable in said casing and positioned for engagement of said armature, an end of said plunger extending through said casing, a second spring, said second spring being stronger than said first spring and engaging said plunger to move said plunger into engagement with said armature to open said switch contacts, a bracket for mounting said casing on said engine, a large-

headed screw connecting said bracket to said casing, the head of said screw extending within and enhancing the effect of said electromagnet, and a coil spring between the outer end of said plunger and said throttle control, tensioning of said coil spring moving said plunger against the resistance of said second spring to permit movement of said contact member to bridge said switch contacts, the strength and initial tensioning of said coil spring being such that the resistance of said second spring is not overcome until said throttle control is in the substantially fully open position, whereby at idling and low engine speeds said second spring is operative to maintain said switch contacts open independent of the influence of said electromagnet on said armature.
